G. A. CARLSON.

HOLDER FOR PENCILS, PENS, &c.
APPLICATION FILED FEB. 18, 1920.

1,365,374.

Patented Jan. 11, 1921.

Inventor:
Gustav A. Carlson.
By appointment, Cotton Mills,
Atkins.

UNITED STATES PATENT OFFICE.

GUSTAV A. CARLSON, OF CHICAGO, ILLINOIS, ASSIGNOR TO THE BOYE NEEDLE COMPANY, OF CHICAGO, ILLINOIS, A CORPORATION OF ILLINOIS.

HOLDER FOR PENCILS, PENS, &c.

1,365,374.

Specification of Letters Patent. Patented Jan. 11, 1921.

Application filed February 18, 1920. Serial No. 359,551.

To all whom it may concern:

Be it known that I, GUSTAV A. CARLSON, a citizen of Sweden, residing at Chicago, in the county of Cook and State of Illinois, 5 have invented a new and useful Improvement in Holders for Pencils, Pens, &c., of which the following is a specification.

This invention relates particularly to holders for pencils, pens, or the like; and the 10 primary object is to provide an improved device of the character indicated, which may be readily applied to a pocket of a vest, coat, or other article of wearing apparel.

The invention is illustrated, in its preferred embodiment, in the accompanying drawing, in which—

Figure 1 represents a broken vertical sectional view of the pocket of a garment, and showing the improved device applied thereto, the view being on an enlarged scale; Fig. 2, a vertical sectional view of the pencil-holder shown in Fig. 1; Fig. 3, a plan view of the same; and Fig. 4, a plan sectional view taken as indicated at line 4 of Fig. 2, 25 but showing the clamping-member in closed position.

In the illustration given, A represents a portion of a garment, such as a vest, or coat, which is provided exteriorly with a pocket 30 A'; and B, the improved pencil-holder adapted to be applied to said pocket.

In the form shown, the device B comprises a pocket-engaging clip 1; a resilient pencil-engaging loop 2 carried thereby; and 35 a clamping-lever 3 carried by the member 1.

The pocket-engaging clip 1 comprises an inverted U-form sheet-metal member having at the upper end a web-portion 1^a and having an outer depending arm 1^b and an inner 40 depending arm 1^c. Between the arms 1^b and 1^c of the clip is a space, or channel, 4, which is open at its lower end; and the arm 1^c has an inclined downward extension 1^d which has the effect of widening the channel at its 45 lower end to facilitate application of the device to a pocket. The space 4 affords a channel which accommodates the upper edge-portion of the pocket A'.

The resilient pencil-holding loop 2 is of 50 well-known construction, and may be secured to the clip 1 in any desired manner. It is usual to form the resilient loop 2 from coiled wire having flattened or substantially rectangular convolutions, that is, coils which 55 are elongated vertically. In the illustration

given, such coiled wire is bent into cylindrical form, and the end loops 2^a and 2^b are caused to engage a small sheet-metal clip 5, whose vertical edge-portions are then secured in channels 6, with which the arm 1^c 60 is provided. This particular feature is a well-known feature of construction.

The clamping-lever 3 preferably comprises a sheet-metal plate, whose lower end is joined, by a pintle 7, to the lower end of 65 the outer arm 1^b of the clip 1. The upper end of the member 3 is equipped with a rearwardly-extending resilient finger-piece 3^a, which is adapted to engage the upper end of the clip 1 and lock the lever 3 in closed 70 position. The member 3 is equipped at an intermediate point with a rearwardly-projecting stud 3^b, which is adapted to work freely through a perforation 8 in the arm 1^b and to press the cloth which may be contained in the channel 4 into engagement 75 with a registering perforation 9 with which the arm 1^c is provided. In other words, the stud 3^b is adapted to project into the space 4 and clampingly engage the cloth of the 80 pocket and force the cloth into the perforation 9, which thus affords a shoulder for engaging the cloth. The stud 3^b is preferably formed by punching the metal of the member 3 rearwardly, as clearly indicated in 85 Fig. 4.

From the description given, it will be understood that the improved device may be applied with great facility to a pocket, and may be removed with equal facility; also, 90 it will be understood that the improved device will securely grip the pocket.

The improved device is small, compact, and may be cheaply manufactured. It renders unnecessary the use of impaling tongs 95 in connection with a shank for securing the pencil-holder to a garment. The secure attachment of the device to a garment is accomplished by a simple clamping action with respect to the cloth of the pocket. 100

The foregoing detailed description has been given for clearness of understanding only, and no unnecessary limitation should be understood therefrom, but the appended claim should be construed as broadly as permissible, in view of the prior art.

What I regard as new and desirable to secure by Letters Patent is:

A device of the character set forth, comprising an inverted U-form clip having its 110

inner arm provided with an inclined downward extension adapted to enter a pocket, a resilient loop mounted on said inner arm, the outer arm of the clip being provided 5 with a perforation, and a lever having its lower end pivotally connected with the lower end of the outer arm and having its upper

end equipped with a resilient finger-piece adapted to engage the upper end of the clip, and having its intermediate portion equipped 10 with a stud adapted to project through said perforation and grip the cloth of the pocket.

GUSTAV A. CARLSON.
